SHIELDED WIRE CONNECTORS**Edgar W. Forney, Jr., Harrisburg, Pa., assignor to
AMP Incorporated****Application July 23, 1954, Serial No. 445,277****18 Claims. (Cl. 174—88)**

The present invention relates to electrical connectors which are crimped onto shielded electrical wires to make permanent, mechanically and electrically secure connections and to the resulting connections and the method and apparatus for making such connections. The connectors described as embodying the invention provide connections both to the inner conductors of shielded wires and to their electrically conductive shields, while maintaining them insulated one from the other. This application is a continuation-in-part of my prior copending application, Serial No. 305,205, filed August 19, 1952 now abandoned.

Among the important advantages of the present invention, are those resulting from the fact that the connectors described are integral. No loose pieces are required to make connections. A splice between two shielded wires is completed merely by crimping one of the connectors described in four places.

Formerly, in many cases connectors for shielded wires were of the separable type involving complicated screw machine parts, often requiring soldering to the inner conductor or shield. Such connections are bulky, expensive, and difficult to make. In other cases, connections for shielded wires have been made by stripping back the shielding a distance, stripping the intermediate insulation from end portions of the inner conductors, twisting and soldering the conductors together, then carefully insulating this joint, and finally joining the two wire shields together by a short length of wire soldered to each shield. The central conductor was often left substantially unshielded at the junction. Where shielding was required, a loose piece of braided shielding was slipped over one of the wires before the connection was made and was bridged between the two shields adjacent the connection and soldered thereto. Such shielding is difficult to handle and readily becomes loose or frayed. Extreme care is required to solder the shielding on the wires without seriously damaging the intermediate insulation, for the large thermal conductivity of the shielding usually requires the application of considerable heat in soldering. Such soldered connections are bulky and awkward; they may be left improperly shielded, and the skilled labor time required is considerable, regardless of how such connections are made.

Crimped connections for shielded wires have been suggested but have required the use of a number of separate pieces. Prior crimped connections have required that the connection be built up step by step, with considerable manipulation of loose pieces, and when the connection was completed there was no solid insulation layer between the inner conductor and shield in the region of the connection.

In order to facilitate the making of shielded-wire connections and ones wherein the inner conductor and the shielding of the shielded wire are positively insulated from one another, I provide unitary connectors which can be used without disassembly, and into which shielded wires, with end portions stripped to expose the inner conductors, may readily be inserted and the assembly easily

2

and quickly crimped to grip and connect both the inner conductors and the shielding.

The described embodiments of the present invention automatically provide continuous shielding of the central conductor as the connection is made. These connectors provide compact, strong connections which have a minimum effect on the characteristic electrical impedance of a shielded wire.

Among the advantages of the present invention are those resulting from the fact that noncollapsible sleeves are inserted under the shielding of the shielded wire in order to back up the forces applied to the shield and protect the insulation of the wire during crimping. These inner sleeves have their ends slanted to facilitate sliding under the shield and to present an effectively larger opening into which to insert the bared end of the inner conductor of the shielded wire being connected.

An advantage of one of the connectors described is that the end of the outer sleeve projects beyond the end of the inner sleeve. This projecting end is adapted to be crimped closely around the shielding beyond the inner sleeve so as in effect to embrace firmly the wire insulation. The result is to clamp the inner conductor of the shielded wire at its entrance into the connection, thus preventing any vibration from travelling therewith along into the connection. As shown, the end of the outer sleeve in this connector is folded back a short distance inside, the resulting double thickness giving firm support to the inner conductor. Advantageously, stepped dies are used to produce a firm support for the inner conductor by this extending end portion of the outer sleeve.

Yet another advantage of this invention is the provision of a connector, and connection made therewith, which enables easy visual inspection of the connection between the inner conductors.

In one of the described connectors, the window in the outer sleeve through which the operator can determine whether the ends of the inner conductors have been fully inserted into the connector, is generally rectangular in outline, thereby providing a view of the ends of the inner conductors extending the full width of the connection. This helps in making a proper connection and greatly aids a wiring inspector, for in many cases he does not have to twist the wire in order to get a good look through the window at the ends of the inner conductors. Also, the rectangular shape of the window is well adapted to coact with the connector-locating fingers used in certain crimping tools in order to locate the connector in proper position between the crimping dies.

Moreover, in the embodiments of the present invention described, the insulation layer in the connector is transparent plastic and is depressed to form a pane within the window closely adjacent the desired position of the inner ends of the conductors to provide a clear view of the ends of the conductors and so that they may be seen from a further lateral position. The longitudinal edges of this window in the outer sleeve of certain embodiments of the connector described are slightly turned in during indenting of the depressed plastic pane to assist in maintaining the depressed area from springback and to help hold plastic insulation layer within the outer sleeve.

A further advantage of the certain connectors described is that the outer sleeves have semi-circular crimps therein over the inner sleeves and positioned near the ends of the insulation sleeve to hold the whole connector assembly firmly together.

Also, the connector is adapted to have a smaller size shield-support in one end for those cases where a smaller shielded wire is connected to a larger one.

A further advantage of one of the described connectors is that the insulation sleeve between the inner and outer conductive ferrule has a thickened central portion, there-

by increasing the strength of the connector and the breakdown voltage of the completed connection.

The various other advantages and aspects of the present invention will be in part pointed out and in part understood from the following description considered in conjunction with the accompanying two sheets of drawings, in which:

Figure 1 is a perspective view of a completed connection between two shielded wires, the connection being formed by a connector embodying the present invention;

Figure 2 is a perspective and sectional view of the connection in Figure 1 taken along the line of 2—2 parallel to the axis of the connection of Figure 1;

Figure 3 is an exploded perspective view of the parts of the connector used in making the connection in Figure 1;

Figure 4 is a perspective sectional view taken longitudinally through the uncrimped connector and showing a shielded wire inserted into the right end of the connector in position to be crimped;

Figure 5 is a cross sectional view taken along the line 5—5 in Figure 1 showing the crimped connection to the inner conductor of a shielded wire;

Figure 6 is a cross sectional view taken along the line 6—6 in Figure 1 showing the crimped connection to the shield braid of a shielded wire;

Figure 7 is a transverse sectional view, on enlarged scale, taken along the line 7—7 of Figure 1 through the window portion of the connector;

Figure 8 is a longitudinal sectional view, on enlarged scale, illustrating the center portion of the uncrimped connector of Figure 3 showing the serrations on the inner ferrule;

Figure 9 is a perspective view of one of the stepped dies used to make the connection to the shielding on the wire;

Figure 10 is an axial view of the upper and lower dies in partially closed position as seen from the large end;

Figure 11 is an axial sectional view, in enlarged scale, of an end of the connection of Figure 1 being completed by the dies of Figures 9 and 10;

Figures 12, 13 and 14 show the embodiments of the present invention disclosed in my above copending application, as follows:

Figure 12 is a longitudinal sectional view through a connector prior to crimping with the end of a shielded wire shown properly positioned for crimping;

Figure 13 is a partial longitudinal sectional view of another embodiment of the invention, this view being similar to the right side of Figure 9, but with the shielding of the wire shown partially broken away and in section and with a shield-supporting sleeve shown inserted under the shielding and

Figure 14 is a cross sectional view through the shield-gripping crimp used with the connector of Figure 12.

In Figures 1 and 2 is shown an easily made, permanent connection formed by crimping an integral connector 11 onto the ends of a pair of shielded wires 10, each including an inner conductor 12, an intermediate insulation layer 14, and an outer conductor shield 16, shown as braided wire. To join the inner conductors 12 of the shielded wires, the connector 11 has an inner conductor ferrule 20 (see also Figures 3 and 4) including two cylindrical ferrule portions 22 which are held in electrical attachment and spaced end-to-end relationship by a joining portion 24. Each of the ferrule portions 22 is adapted to be slid over the bared end of an inner conductor 12, as shown most clearly in Figure 4, and to be crimped thereto by crimping forces applied to the outside of the integral connector 11 to form crimps 25 (Figure 5). Advantageously, there is no need to disassemble the connector or to build up the connection step by step to make the connection. The inner conductor ferrule 20 may be rolled from a blank stamped from sheet metal stock, the resulting seam 23 being shown in Figure 5.

To insulate the inner conductor ferrule 20 from the other portions of connector 11 and automatically to insure an effective continuation of the insulation 14 throughout the length of the connection, an insulation sleeve 32 of tough transparent plastic is placed over ferrule 20 (Figure 3), and is held in position by external serrations 21 on the outer surfaces of both ferrule portions 22. In assembling this plastic sleeve 32 and the inner ferrule 20 into an integral component, the ferrule 20 is press fitted into the plastic sleeve. Then the ferrule is induction heated to soften the plastic in contact with the ferrule portions 22, causing the softened plastic to flow into the serrations to produce a mechanical lock between the ferrule and plastic sleeve. Sleeve 32 is of a material sufficiently tough to withstand the compression forces of a crimping operation without undue loss of resistance to voltage breakdown. In a commercial form, it is of transparent nylon.

Generally, the materials suitable for use in insulation sleeve 32 are those that can withstand the pressures during crimping of enclosed metal connection assemblies and may be from a class of insulation materials which are very tough and sufficiently malleable (capable of being pressure-formed without rupture) at ordinary temperatures to be compressively deformed and set during the crimping operation. The workable materials have been found to reside in that group of plastics commonly referred to as rigid, including such superpolymers as vinyl chloride, slightly plasticized, vinyl chloride-vinyl acetate copolymers, vinylidene chloride, and nylon. Softer materials may tend to be squeezed out of place too readily. Another advantage of my connector is that the outer shield ferrule 34 protects insulation sleeve 32 from direct contact with the crimping dies and tends, by its frictional contact, to retard the extrusion of the insulation material. Thus it permits a thinner or softer sleeve 32 to be used than customarily would be used in insulated connectors without such an outer ferrule, to reduce the overall diameter of the connection.

The form of crimp 25 (Figure 5) used in compressing the central conductor ferrule portions 22 by means of pressure applied through the tubular insulation sleeve 32 is important in providing the desired electrical and mechanical properties and the preferred crimp is particularly protective of the sleeve 32, as described in detail herein-after.

The outer surface on the ferrule portions 22 should be fairly smooth, as shown in Figure 5, to protect the insulation sleeve 32 from local areas of unduly high pressure during the crimping operation. The serrations 21 are of the type leaving lands of trapezoidal cross section so that the outer surfaces of ferrule portions 22 remain in effect substantially smooth.

The central conductor ferrule 20 is made of electrically conductive and malleable metal; soft copper and brass can readily be used. The malleability should be such that the ferrule 20 can be compacted against and cold-flowed into intimate contact with the conductors 12. High conductivity, such as that of copper, minimizes the size of the ferrule 20.

The inner surfaces of the ends of the ferrule portions 22 advantageously provide funneled entrances 28 to their bores 30 to help in sliding in the bared ends of the inner conductors 12, which is particularly helpful when these inner conductors are finely stranded. It is also desirable to have the bores 30 of the ferrule portions 22 provided with transverse serrations 31, similar to serrations 21 to increase the tensile strength of the connection.

A malleable outer conductive shield 34 forms the casing for the connector, with its ends extending beyond the ends of insulation sleeve 32. In completing the connection, the ends of outer sleeve 34 are each triply folded in two places and collapsed inwardly to embrace the shielding 16 on the wire, as described in detail herein-after. The shielding 16 is backed up during the crimp-

ing operation by a relatively rigid shield-supporting sleeve 35 of drawn seamless tubing secured within each end of the connector. Each of sleeves 35 has an enlarged inner end fitted into an annular recess 37 to grip the reduced outside diameter of the end of the insulation sleeve 32, which is tapered at about a 30° angle for a short length on its outer surface to aid in sliding the sleeves 35 thereon.

As seen most clearly in Figure 4, a shoulder 38 formed by the transition between the enlarged and reduced ends of sleeve 35 forms an annular abutment for stopping the shielding 16 and may advantageously be used for sliding the shielding 16 back from the end of the wire 10 as the wire 10 is inserted into connector 11. Abutment 38 properly positions the end of the shielding within the completed connection, maintaining the desired spacing between ferrule 20 and shield 16. The outer ends 39 of shield-supporting sleeves 35 are cut off at an angle of about 75° to the connector axis and have an inside diameter approximately equal to the inside diameter of the inner surfaces 33 of the ends of the insulation sleeve 32 extending beyond the ends of the ferrule portions 22, to form an effectively continuous bore for receiving the wire insulation 14. Preferably the inside diameter of ends 39 is only slightly larger than the insulation 14 so as firmly to embrace insulation 14 (see Figure 6) after the shield-gripping crimp is made, for example, as shown by the dotted outline (Figure 4) of the end 39 of the sleeve 35 in the right side of the connector 11.

The slanted ends 39 of sleeves 35 are helpful in furnishing a "lead" so that ends 39 may readily be slid underneath shield braid 16 adjacent the intermediate insulation 14, without any snagging of the shield braid thereon. Also, with the ends 39 slanted, shown at about a 75° angle, the elliptical opening into sleeve 35 is somewhat longer than its actual inside diameter, which further aids in the insertion of the ends of conductors 12 and their insulation 14. To help in the assembly of the wires 10 and connector 11, the elliptical openings in slanted ends 39 may face in the same direction as window 40.

As shown in Figures 2 and 4, a particular advantage of connector 11 is that after crimping the slanted ends 39 of the supporting sleeves 35 do not project beyond the skirt 42 on the ends of the outer ferrule 34. Thus, when the wire 10 is subjected to a sideward pull or is bent over adjacent the connection, the shielding 16 on the inner side of the bend is subjected to a compressive force to form a radius so as to protect the insulation sheath on the inside of the bend, while the shielding 16 on the outside of the bend is under tension from the closely adjacent grip of the crimped skirt 42 and resists the bending force, making the bend in the shielded wire more gradual, to provide further protection.

The extending end of the skirt 42 is folded back to produce a double thickness bead 49 which is crimped down firmly against the shielding beyond the end 39 of the inner sleeve 35 as shown in Figure 11 and described hereinafter in detail. The inner surface of shoulder 38 abuts the end of sleeve 32, thus holding sleeve 35 firmly in place against the force exerted by the shielding on the outside of shoulder 38 as wire 10 is inserted.

As mentioned above, insulating sleeve 32 is transparent and a central window aperture 40 is provided in outer sleeve 34 adjacent the opening in ferrule 20 and opposite to the joining portion 24. It is rectangular and extends substantially across one side of the connector 11. The inserted ends of the inner conductors 12 may be readily seen through window 40 to make certain they are properly inserted.

The area of the sleeve 32 extending across the window 40 forms a plastic pane 43. In assembling the connector, the sleeve 32 is formed around ferrule 20 in tubular form and then is inserted into the outer ferrule 34. The window 40 initially extends less than half way around the circumference of the outer sleeve. After assembly

of the parts of Figure 3, a flat edge extending transversely of the connector is used to indent the pane 43 flat (see Figure 7) over its full width and the two longitudinal edges 41 of the outer ferrule 34 extending parallel to the axis of the connector are rolled over onto the opposite edges of the pane 43 as shown most clearly in Figure 7. These rolled over edges 41 help to secure the outer ferrule 34 and the sleeve 32 together as an integral unit and help hold the pane 43 depressed.

10 The exploded view in Figure 3 shows sleeve 32 as it appears after assembly inside of the outer ferrule 34. Prior to assembly the sleeve 32 would not have the depressed pane 43.

15 The extreme ends of the outer shield ferrule 34 are flared outward, at least on their inner surface, and advantageously may have a full flared skirt 42 as shown in Figure 4, to provide a funneled entrance to their central bore 44. These funneled entrances 42 facilitate the insertion of the wire shields 16 into the shield ferrule 34 20 so that as the shielded wire is inserted the funneled entrances 33 and 28 guide the bared ends of inner conductors 12 into the ferrule portions 22, and the skirt 42 gathers in the end of shield 16, causing it to strike abutment 38. This enables the easy insertion of the shielded wire while preventing the inward movement of the braided wire shield 16 beyond abutment 38.

25 The whole connector 11 is held rigidly together by pairs of wide semi-circular crimps 47 which grip the enlarged inner ends of the sleeves 35 near the abutments 38 and help to align the sleeves 32 and 35 after their initial assembly into the outer ferrule 34. These flat crimps 47 may be run about half-way around the top and bottom of the sleeve 34 near the shoulder 38 in the braid-supporting sleeves 35.

30 In order to simplify the connection of shielded wire, I have developed a novel method which in many applications obviates any preliminary cutting back of the braided-wire shield. If there is any insulation over the shield-braid it is, of course, stripped back a ways from the end 40 of the shield-braid. This method consists of gripping the shielded wire a distance from its end in one hand and sliding the shielding back from the end with the other hand. With the intermediate insulation 14 (see Figure 4) thus exposed, this insulation 14 may then be severed 45 and removed from an end portion of the conductor 12 by convenient insulation stripping means. Thereafter, when the shielded wire is inserted into one end of a connector as described, the insulation 14 is allowed to enter sleeves 35, but the shield 16 must slide onto it while insulation 14 slides into the connector until it reaches a position adjacent the restricted region near the end of ferrule portion 22.

50 The bared ends of conductors 12 are inserted a bit beyond the adjacent ends of the ferrule portions 22 in order than the ends of the conductor may be clearly seen through window 40. This is advantageous in ascertaining that a connection has been properly assembled before crimping, as well as in inspecting completed connections.

55 60 When both wires 10 have been inserted into the connector 11, it is pressure-formed or crimped in four places, 48, 25, 25, and 48, respectively, longitudinally spaced therealong to form a permanent connection as is shown in Figures 1 and 2.

65 70 Different types of crimps are preferred for gripping inner conductors 12 and for securing the shield 16. Referring to Figures 1 and 2, the central areas 25 of the shield ferrule 34, adjacent window 40 and overlying the central conductor ferrule portions 22 are advantageously crimped to a flattened, generally elliptical cross-sectional shape as shown in Figure 5. The advantage of this elliptical crimp, made with smoothly curved die surfaces confined at their sides during crimping, is that it maintains a substantially even thickness of the insulation sleeve 32 while the ferrule portions 22 and central con-

ductors 12 are compacted tightly together. This crimp is more fully disclosed and is claimed in the copending application of Clyde N. Holtzapple, Serial No. 73,946, filed February 1, 1949, and assigned to the same assignee as the present invention.

The outer shield ferrule 34 is advantageously crimped by a crimp 48, to collapse the skirted ends 42 firmly against the braided shields 16 and to grip the shields 16 as shown in Figure 6. The crimp 48 shown collapses the shield ferrule inwardly at side portions 50 and forms and compacts top and bottom portions 52 around the braided shielding 16. In this fashion the braided shielding is firmly gripped between the shield ferrule 34 and the shield support 35 without appreciably deforming the shield support or reducing the thickness of the intermediate insulation sheath 14 or changing its circular shape. This crimp 48 is particularly advantageous in forming connections with connectors in which the end of shield ferrule 34 is generally considerably larger than the shield braid to be received therein, for example, where a full skirted flare 42 is provided on the ends of outer sleeve 34.

The crimp 48 includes projecting re-entrant folds 68 and an inner folded junction 70, thus producing a triply folded region on opposite sides of the ferrule. The advantage of forming this crimp is that I am able to collapse a shield ferrule onto a flexible metallic wire shield merely by impressing it between two laterally confined die surfaces as described in my said prior copending application and to get compression between the inner folded junctions 70 and the wire shield 16 which compression actually is acting in a direction perpendicular to the compression force of the dies. Thus, the wire shield 16 is compressed between the shield ferrule 34 and the intermediate insulation sheath 14 about substantially all of its circumference without imposing high pressure on this part of my connection assembly. This in turn is important because high crimping pressures would tend to buckle the braid supports 33 and then to extrude, thin, and otherwise weaken the intermediate insulation sheath 14.

The connection to the shield braid as shown in the preceding figures is crimped by the upper and lower dies 82 and 84, respectively, shown in Figures 9, 10, and 11. The upper die includes two flat crimping shoulder surfaces 86 on either side extending perpendicular to the direction of closure of the dies.

Between the shoulder surfaces 86 extend two concave cylindrical crimping surfaces 88 and 90 having the same transverse extent, defined by the edges 91. The concave surfaces 90 has an effective radius about 20 to 50 percent smaller than the radius of the surface 88, depending upon the connector dimensions, so that it extends up further into the die 82, leaving a crescent shaped step 92. The lower die 84 has crimping surfaces which are identical with the upper die and are similarly numbered, except that the lower die additionally includes two spaced upwardly extending legs 94 on each side which provide uniformly spaced flat side walls 96 for confining the skirt 42 during crimping. The smoothly curved portions 90 press the skirt 42 into conforming pressure contact with the shield braid 16 while the flat regions 36 and the edges 91 frictionally pull the skirt 42 around opposite sides of the shield braid 16, thus acting with the parallel confining surfaces 96 to buckle the skirt 42 and form the opposed triple-folded regions 50 as shown in Figure 6.

At the same time the more-shallow concave surface 88 crimps the beaded edge 49 firmly down against the shield braid 16 beyond the end 39 of the inner sleeve firmly to confine the insulation layer 14 and conductor 12 at the region of entry into the connection. The resulting confined areas 98 in the insulation layer 14 advantageously damp out any vibrations in the inner conductor 12 and prevent them from entering the connection. The extra thickness in the bead 49 causes the outer end portion of the inner fold 70 to extend in toward the conductor 12

somewhat further than the rest of the fold 70 so that the confined regions 98 effectively extend completely around the conductor 12 enhancing the desired damping support action by the insulation 14.

5 The dies 82 and 84 are shown as being laminated, formed by pairs of parallel plates, 100 and 102, and 104 and 106, respectively, fastened together by means not shown to move as integral dies.

10 Among the other advantages of connector 11 is that it is relatively small in size and is readily adapted to a range of wire sizes. Also, it may be used to connect different sizes of wire in its opposite ends. For example, the inner ferrule 20 can accommodate a range of three sizes of wire, such as 18 through 22. The full skirts 42 can accommodate a wide range of sizes of shielding 16, and while shield-supports 35 are generally enabled to support a more limited range of shield sizes, connector 11 is adapted to receive a wide range of sizes of supports 35.

15 In a commercial form, sleeve 34 and ferrule 20 are made from annealed copper, while shield-supports 33 were made from 70/30 fine grain cartridge brass $\frac{1}{4}$ hard, stress relieved for one hour at 475° F.

20 For use with shielded wires having inner conductors

25 12 in the size range from 18 to 22, the following dimensions and sizes for connector 11 may be used to produce highly satisfactory connections. Sleeve 34 may have a wall thickness of .010 inch, a length of 1.515 inches, an inside diameter of .197 inch, and an outside diameter 30 at the mouth of skirt 42 of .285 inch. Inner sleeve 20 may be about a half an inch long, for example, being .508 inch long with an inside diameter of at least .061 inch and an outside diameter of no more than .136 inch. The insulation sleeve 32 may have an over-all length 35 of 1.015 inches, with the enlarged center portion being somewhat longer than ferrule 20, for example, being .515 inch long with the overhanging end portions of reduced diameter each being about a quarter of an inch long, and the length of the external taper being .062 inch. The wall thickness of the enlarged center portion 40 of sleeve 32 may be in the range from .028 to .031 inch depending upon the tolerances of the ferrule 20 and sleeve 34.

25 The shield supports 33 may be about .395 inch long 45 with their enlarged end adapted to fit snugly within the end of sleeve 34. The length of the enlarged portion may be about .187 inch long and the length of the reduced portion 45 may be about .208 inch. Its wall thickness is about .01 inch and the inside diameter of the

50 reduced end 45 is in the range from about .090 to .120 inch, depending upon the diameter of the insulation 14 with which they are to be used. I now prefer to cut off the end 39 of the inner sleeve 35 at an angle of about 55 75° to the connector axis, but a more gradual inclination may be obtained, if desired, by using an angle in the range from about 45° to 75°, for example, an angle of 60° has advantages for some applications. In some instances it is desirable to have the end 39 cut off parallel with the head 49 on the skirt 42.

60 In Figures 12, 13, and 14, are shown other embodiments of the present invention. Figure 12 shows a unitary connector 11a generally similar to connector 11. For convenience, portions of connectors 11a performing functions similar to connector 11 have the same reference numeral with the suffix "a." The cylindrical ferrule

65 portions 22a are enclosed in seamless (drawn) sleeves 26, which sleeves comprise part of many standard types of ferrules. These sleeves 26 are a means of providing a very smooth outer surface on the ferrule portions 22a and when used are considered part of the ferrule portions 22a in the further discussion and in the accompanying claims along with any other means for accomplishing the same result (e.g. having ferrule portions 22a drawn rather than rolled, or using carefully brazed and 70 polished ferrules, etc.).

The insulation sleeve 32a is a length of plastic tubing of one of the tough plastic materials discussed above with its ends projecting beyond the ends of the ferrule 20a. To hold ferrule 20a firmly within sleeve 32a, a pair of spacing tubes 36 are held in abutting or closely adjacent end-to-end relationship with each of the extreme ends of the ferrule 20a by means of pressed detents 57 in the shield ferrule 34a and tubular sleeve 32a which impose sufficient pressure on the spacing tubes 36 to hold them securely in place.

The length of these tubes 36 is such that, when so held, their extreme ends coincide with the ends of the sleeve 32a to provide transverse annular abutments 38a spaced inwardly from each end of the shield ferrule 34a. The spacing tubes 36 are of nonconductive material, preferably being short lengths of extruded plastic tubing which are quite stiff at ordinary temperatures. These tubes have various functions, the provision of the annular abutment 38a as a shield stop advantageously in combination with the ends of the tubular sleeve 32a, being their primary function. The spacing tubes provide a high dielectric, high breakdown voltage, and longer current creepage path between the central ferrule 20a and the wire shielding 16a which is abutted against the annular abutment 38a. These tubes 36 also form guides for the intermediate insulation sheath 14a which help locate the central conductor 12a in the central ferrule 20a during assembly of a connection.

Some type of shielded wire may have a protective outer coating of insulation 18 as shown in phantom lines in Figure 12 and in some circuits the shielding 16a of such wires may be operated at other than the potential of the chassis on which the shielded wire 10 is located. In a situation such as this, the shield ferrule 34a may be enclosed in an outer sheath 19 as shown in phantom lines of the tough, rigid, and substantially malleable insulation material which would remain undamaged after the crimping operation. In order to make the connection, external insulation sheath 18 is stripped back from the shield braid 16a so as substantially to abut the end of the flared skirt 42a on connector 11a so that when the connection is completed there is substantially no gap in the outer insulation provided by sheaths 18 and 19.

Figure 14 is a cross-sectional view through one of the skirt portions 42a of connector 11a after being crimped to the shield braid 16a. Connector 11a has no shield support, the compression of the crimp being borne fully by the intermediate insulation 14a. In this unsupported shield connection, the triple-folded type of crimp discussed above is also very advantageous for it causes the shield 16a to grip the intermediate insulation around substantially its entire circumference thereby giving the maximum support to the insulation 14a. This is important because some shielded wires have insulation sheaths which are subject to cold flow after being compressed and which tend to gradually flow from under the shield 16a where it is compressed against the intermediate insulation sheath by the crimped skirt portion of shield ferrule 34a, thus tending to release at least partially the binding pressure between the shield ferrule 34a and the wire shield 16a, causing a poor electrical contact and lowered mechanical strength at this shield connection. Such reduced contact pressure may cause "noise" in electrical communication circuits. The present form of crimp minimizes this creeping of the intermediate insulation sheath, and wherever there may be any tendency to loosen, a connector such as connector 11a with shield supporting sleeves may be used to maintain full crimping pressure between the collapsed skirt 42a of shield 34a and the shield braid 16a.

Another form of connector is illustrated in Figure 13 parts performing functions similar to Figure 12 have corresponding reference numbers with the suffix "b." A shield braid support 72 is provided which fits between the intermediate insulation sheath 14b and the braided wire or

other flexible metallic shielding 16b. This support sleeve 72 is advantageously made of a hard metal, hard brass, or steel being preferred, in order to permit the shield ferrule 34b and 16b to be crimped thereagainst without undue transmission of the crimping pressures to the intermediate insulation sheath. The cylindrical sleeve 72 is disposed coaxially within the extended end of the shield ferrule 34b and held therein by an annular flange or ridge 74 which is force-fitted into the shield ferrule 34b and abutted against the end of the tubular insulation sleeve 32b. The outer transverse surface of the annular ridge 74 provides the annular abutment 38b against which the braided-wire shielding 16b is abutted during assembly of a connection. The outer end of the sleeve 72 is provided with a tapered or chamfered outer surface 78 which provides a tapered approach from the inner surface 80 to the outer surface 82, which surfaces 80 and 82 are generally cylindrical. This tapered approach advantageously projects outwardly beyond the end of the shield ferrule 34b in order to enable one making a connection assembly to work the braided-wire shield 16b over the sleeve 72 with their fingers if it does not slide up over the tapered approach easily upon insertion of the shielded wire. Many shielded wires have such dimensions and intermediate insulation sheaths of such material that they may be used for transmission lines, in which case they are often referred to as coaxial cables. As used herein the term "shielded wire" is intended to include any wire or cable having at least one inner conductor spaced from and at least partly surrounded by an outer conductor, often insulated therefrom by a continuous layer of insulation 14.

From the foregoing, it will be understood that the connectors, connections, method and apparatus described above are well suited to provide the advantages set forth, can be manufactured readily by conventional fabrication techniques and that the various features and arrangements of parts may be modified to various particular shielded wire applications whereby the operator is enabled to complete good electrical and mechanical connections to shielded wire with a unitary connector. Certain features of the connectors and connections described may be used to advantage in particular applications without the use of other corresponding features and are to be considered within the scope of my invention unless specifically excluded by the following claims or required by the scope of the prior art.

What is claimed is:

1. An electrical connector for shielded wires and the like having an inner conductor and an outer conductor shield surrounding said inner conductor and insulation therebetween, said connector comprising a malleable conductive inner ferrule having a longitudinal bore adapted to receive and be crimped to an inner conductor of the shielded wire, a relatively elongated insulation sleeve of tough, malleable, insulation material surrounding said ferrule and secured thereon and having an end portion extending beyond the end of said inner ferrule, a malleable conductive outer ferrule substantially surrounding said insulation sleeve and secured thereon and having a skirted end portion extending beyond the end portion of said insulation sleeve adapted to embrace the end of the conductor shield of the shielded wire, and a relatively rigid support for supporting the conductor shield of the shielded wire during a crimping operation, said support having a first end of enlarged inside diameter embracing the projecting end of said insulation sleeve and extending into said outer ferrule further than its skirted end portion and having a second end of reduced outside diameter having a bore aligned with the bore of said inner ferrule, said second end being adapted to be inserted between the conductor shield and the insulation of the shielded wire.

2. An electrical connector for shielded wires and the like having an inner conductor and an outer conductor shield surrounding said inner conductor and insulation

therebetween, said connector comprising a malleable conductive inner ferrule having a longitudinal bore adapted to receive and be crimped to an inner conductor of the shielded wire, a relatively elongated insulation sleeve of tough malleable insulation material surrounding said ferrule and secured thereon and having an end portion extending beyond the end of said inner ferrule, a malleable conductive outer ferrule substantially surrounding said insulation sleeve and secured thereon and having a skirted end portion extending beyond the end portion of said insulation sleeve adapted to embrace the end of the conductor shield of the shielded wire, and a relatively rigid support for supporting the conductor shield of the shielded wire during a crimping operation, said support having a first end of enlarged inside diameter embracing the projecting end of said insulation sleeve and extending into said outer ferrule farther than its skirted end portion and having a second end of reduced outside diameter having a bore aligned with the bore of said inner ferrule said second end being adapted to be inserted between the conductor shield and the insulation of the shielded wire, the second end of said support being slanted to facilitate its insertion under the conductor shield of the shielded wire.

3. An electrical connector for shielded wires and the like having an inner conductor and an outer conductor shield surrounding said inner conductor and insulation therebetween, said connector comprising a malleable conductive inner ferrule having a longitudinal bore adapted to receive and be crimped to an inner conductor of the shielded wire, a relatively elongated insulation sleeve of tough malleable insulation material surrounding said ferrule and secured thereon and having an end portion extending beyond the end of said inner ferrule, a malleable conductive outer ferrule substantially surrounding said insulation sleeve and secured thereon and having a skirted end portion extending beyond the end portion of said insulation sleeve adapted to embrace the end of the conductor shield of the shielded wire, and a relatively rigid support for supporting the conductor shield of the shielded wire during a crimping operation, said support having a first end of enlarged inside diameter embracing the projecting end of said insulation sleeve and extending into said outer ferrule farther than its skirted end portion, said outer ferrule being crimped to the first end of said support to secure it firmly within the outer ferrule, said support having a second end of reduced outside diameter having a bore aligned with the bore of said inner ferrule, said second end being adapted to be inserted between the conductor shield and the insulation of the shielded wire.

4. An integral electrical connector for shielded wires and the like having an inner conductor and an outer conductor shield surrounding said inner conductor with insulation therebetween, said integral connector comprising a malleable conductive inner ferrule adapted to receive and be crimped to an inner conductor of the shielded wire, an insulation sleeve of tough malleable insulation material surrounding said inner ferrule and being secured thereon, said insulation sleeve having an end portion extending beyond the end of said ferrule with an annular recess around its projecting end, a malleable conductive outer ferrule substantially surrounding said insulation sleeve and being secured thereon and having an end portion extending beyond the end portion of said insulation sleeve, and a relatively rigid supporting sleeve for supporting the conductor shield of the shielded wire during a crimping operation, said supporting sleeve having a first end of enlarged inside diameter engaging in said annular recess and having a second end of reduced outside diameter adapted to be inserted between the conductor shield and the insulation of the shielded wire, an external abutment on said supporting sleeve intermediate its ends, said outer ferrule being crimped into engagement with said supporting sleeve adjacent said abutment.

5. A connector as claimed in claim 4 and wherein the

external abutment on said supporting sleeve comprises an annular shoulder forming a transition region between its first and second ends.

6. An integral electrical connector for shielded wires and the like having an inner conductor and an outer conductor shield surrounding said inner conductor with insulation therebetween, said integral connector comprising a malleable conductive inner ferrule adapted to receive and be crimped to an inner conductor of the shielded wire, an insulation sleeve of tough malleable insulation material surrounding said inner ferrule and secured thereon, said insulation sleeve having an end portion extending beyond the end of said ferrule, a malleable conductive outer ferrule substantially surrounding said insulation sleeve and secured thereon, and having a full skirted end adapted to receive the conductor shield of the wire, and a relatively rigid supporting sleeve for supporting the conductor shield of the shielded wire during a crimping operation, said supporting sleeve having a first end of enlarged inside diameter embracing the end portion of said insulation sleeve and a second end of reduced outside diameter adapted to be inserted between the conductor shield and the insulation of the shielded wire, said full skirted end extending beyond the end portion of said insulation sleeve and also beyond the second end of said supporting sleeve, whereby to embrace and support the conductor shield of the shielded wire when crimped thereto.

7. An integral electrical connector for shielded wires and the like comprised of a malleable conductive inner ferrule having two electrically connected ferrule portions in end-to-end spaced relationship with an opening therebetween, said ferrule portions having longitudinal bores each adapted to receive and be crimped to the inner conductor of a shielded wire, a relatively elongated sleeve of tough malleable transparent insulation material surrounding said inner ferrule and extending a distance beyond the extreme ends thereof, and a malleable conductive outer ferrule surrounding said transparent sleeve and extending a distance beyond the ends thereof and being flared outwardly at the ends thereof, at least on its inner surface, to form a wire-shield-engaging portion for engaging the shielding of a shielded wire, said outer ferrule having a central window therein adjacent the opening in said inner ferrule, said transparent sleeve being depressed transversely in the area of said window at least partially into said opening, whereby said depressed region of the sleeve forms a pane in said window closely adjacent the bores of said inner ferrule portions.

8. An integral connector as claimed in claim 7 and wherein said sleeve as seen in cross section in the region of said window has a generally semicircular appearance.

9. An integral electrical connector for shielded wires and the like comprised of a malleable conductive inner ferrule having two electrically connected ferrule portions in end-to-end spaced relationship with an opening therebetween, said ferrule portions having longitudinal bores each adapted to receive and be crimped to the inner conductor of a shielded wire, a relatively elongated sleeve of tough malleable transparent insulation material surrounding said inner ferrule and extending a distance beyond the extreme ends thereof, a malleable conductive outer ferrule surrounding said transparent sleeve and extending a distance beyond the ends thereof and being flared outwardly at the ends thereof, at least on its inner surface, to form a wire-shield-engaging portion for engaging the shielding of a shielded wire, said outer ferrule having a central approximately rectangular window therein adjacent the opening in said inner ferrule, said transparent sleeve being depressed transversely in the area of said window at least partially into said opening, to form a pane in said window closely adjacent the inner ends of the bores of said inner ferrule portions, the opposite edges of said outer ferrule extending parallel to the axis of said connector in the region of the

window being rolled over onto the adjacent edges of the pane portion of said sleeve.

10. An integral electrical connector for shielded wires and the like comprised of a malleable conductive inner ferrule having two electrically connected ferrule portions in end-to-end spaced relationship with an opening therebetween, said ferrule portions having longitudinal bores each adapted to receive and be crimped to the inner conductor of a shielded wire, a relatively elongated sleeve of tough malleable transparent insulation material fitting around said ferrule portions and having open ends extending beyond the extreme ends of said ferrule portions, and a malleable conductive outer ferrule surrounding said transparent sleeve and extending a distance beyond the ends thereof and being flared outwardly at the ends thereof, at least on its inner surface, to form a wire-shield-engaging portion for engaging the conductor shield of a shielded wire, said outer ferrule having a central window therein adjacent the opening in said inner ferrule, said transparent sleeve being depressed in the area of said window into said opening to form a pane in said window closely adjacent the inner ends of the bores of said inner ferrule portions, and a pair of supporting sleeves, each having a first end between the outer surface of an end of said transparent sleeve and said outer outer ferrule and each having a second end projecting outwardly coaxially with an open end of said transparent sleeve, said outer ferrule being crimped into engagement with the inner end of each of said supporting sleeves by a pair of opposed approximately semi-circular crimps.

11. An integral electrical connector for shielded wires and the like comprised of a malleable conductive inner ferrule having two electrically connected ferrule portions in end-to-end spaced relationship with an opening therebetween, said ferrule portions having longitudinal bores each adapted to receive and be crimped to the inner conductor of a shielded wire, a relatively elongated sleeve of tough malleable transparent insulation material fitting around said ferrule portions and having open ends extending a distance beyond the extreme ends of said ferrule portions, a malleable conductive outer ferrule surrounding said transparent sleeve and extending a distance beyond the ends thereof and being flared outwardly at the ends thereof, at least on its inner surface, to form a wire-shield-engaging portion for engaging the conductor shield of a shielded wire, said outer ferrule having a central approximately rectangular window therein adjacent the opening in said inner ferrule, said transparent sleeve being depressed in the area of said window into said opening to form a pane in said window closely adjacent the inner ends of the bores of said inner ferrule portions, the longitudinal edges of said outer ferrule adjacent said window being rolled over onto the adjacent edges of the pane portion of said sleeve, and a pair of supporting sleeves for supporting the conductive shields of the shielded wires during a crimping operation, each of said supporting sleeves having an inner end of enlarged diameter surrounding the extending end of said insulation sleeve and having an outer end of reduced diameter adapted to be inserted between the conductor shield and the insulation of a shielded wire, the outer end of said shield supporting ferrule being cut off at an angle to form an elliptical opening to facilitate insertion under a conductor shield of a wire.

12. A connector as claimed in claim 11 and wherein the elliptical opening on the ends of said supporting sleeves face in substantially the same direction as said window.

13. An electrical connector for shielded wires and the like comprised of a malleable metal central conductor ferrule having a cylindriform bore, said bore being outwardly flared at the extreme ends thereof to form funneled entrances thereto, a relatively elongated tubular sleeve of very tough, rigid and substantially malleable insulation material surrounding said ferrule and extend-

ing a distance beyond the extreme ends thereof, and a shield ferrule of malleable metal surrounding said tubular sleeve and extending a distance beyond the end thereof to form wire-shield-engaging portions, said shield ferrule being flared outwardly at the ends thereof, at least on its inner surface, to form funneled entrances to said wire-shield-engaging portions and means at each end of the shield ferrule for preventing the central ferrule from contacting the shielding on the wires.

10. 14. An electrical connector for shielded wires and the like comprised of a malleable metal central conductor ferrule, a relatively elongated tubular sleeve of very tough, rigid and substantially malleable insulation material surrounding said ferrule and extending a distance beyond at least one end thereof, a shield ferrule of malleable metal substantially surrounding said tubular sleeve and extending a distance beyond the extended end thereof to form a wire-shield-engaging portion, and a generally cylindriform shield support disposed coaxially within said wire-shield-engaging portion, said shield support having a cylindriform bore and an outer, generally cylindriform, surface contiguous with the inner surface of the shield ferrule, said outer surface being tapered toward said bore at the extreme outer end of said shield support so that the tapered portion of the shield support and the inner surface of the shielding ferrule form a space to receive the shielding on the wires, and said shield support having an annular ridge adjacent the extended end of said tubular sleeve, said ridge extending from said outer surface to said shield ferrule, said annular ridge presenting a transverse annular abutment between said outer surface of said shield support and the inner surface of said shield ferrule.

35. 15. An electrical connector for shielded wires having an inner conductor, an outer conductive braid, and an insulation layer therebetween, comprising an inner malleable metal ferrule, a relatively elongated sleeve of tough malleable plastic surrounding said ferrule and extending a distance beyond the end of said inner ferrule, and a tubular braid-support having a first free end extending beyond the end of said insulation sleeve, an outer malleable metal sheath surrounding said sleeve and extending a substantial distance beyond the end of braid support, said sheath being flared outwardly at its extending end 45 with the edge of the end of said sheath being curled back over itself to form a double thickness bead.

16. An electrical connector for shielded wires having an inner conductor, an outer conductive braid, and an insulation layer therebetween comprising an inner malleable metal ferrule, a relatively elongated sleeve of tough malleable plastic surrounding said ferrule and extending a distance beyond the end of said inner ferrule, and a tubular braid-support having a first free end extending beyond the end of said insulation sleeve and cut off at 55 an angle in the range from 45° to 75° with respect to the connector axis, an outer malleable metal sheath surrounding said sleeve and extending a distance beyond the end of said braid support, said sheath being flared outwardly at its extending end with the end of said sheath 60 being curled inwardly tight against itself to form a double thickness bead, said bead being positioned entirely beyond the first free end of said braid support.

17. An electrical connection to the end of a shielded wire having an inner conductor, a conductive shield therearound, and an insulation layer therebetween comprising an inner ferrule crimped to the bared end of said inner conductor, an insulation sleeve surrounding said inner ferrule and having an end overlying the adjacent end of said insulation layer, a tubular shield support having 65 a first end around said insulation layer beneath said shield and a second end overlying said end of the insulation sleeve, and an outer ferrule overlying said insulation sleeve, said shield support and said shield, said outer ferrule projecting over said shield beyond the first 70 end of said shield support, said outer ferrule being 75

crimped firmly down against areas of said shield over the first end of said shield support and the projecting portion of said outer ferrule being crimped down firmly against said shield near the first end of said shield support.

18. A solderless crimped electrical connection between an electrical connector and a shielded wire having an inner conductor and an outer conductor surrounding said inner conductor in substantially concentric relationship therewith and insulation means supporting said outer conductor in insulated spaced relationship around said inner conductor, said connector including an inner malleable tubular metal ferrule, an outer malleable tubular metal ferrule having its end projecting a distance beyond the end of the inner ferrule, and tough rigid substantially malleable insulation material surrounding said inner ferrule and supporting said outer ferrule in concentric relationship therewith, said inner ferrule, insulation material and outer ferrule forming an integral connector unit, said insulation material including a portion continuing beyond the end of the inner ferrule and terminating inside of the outer ferrule at a position longitudinally between the end of the inner ferrule and the end of the outer ferrule, said inner ferrule surrounding a bare end portion of the inner conductor of the shielded wire and being deformed into intimate engagement with the inner conductor by deformation of the outer ferrule and of the insulation material, said outer ferrule surround-

5 ing an end portion of the outer conductor and being deformed into intimate engagement with the outer conductor, the portion of the insulation material beyond the end of the inner ferrule providing insulation spacing preventing the entry of the outer conductor into the outer ferrule beyond said insulation spacing and holding said outer conductor longitudinally offset from the end of the inner conductor, thereby assuring that said outer conductor remains spaced away from conductive engagement with the inner ferrule so as to prevent a short circuit between the inner and outer conductors.
